CLAIM

The ornamental design for the head rest cover, as shown and described.

DESCRIPTION

FIG. 1 is a perspective angled front view of the head rest cover, which embodies my design;

FIG. 2 is a rear perspective view thereof;

FIG. 3 is a top view thereof;

FIG. 4 is a bottom view thereof;

FIG. 5 is a front view thereof;

FIG. 6 is a rear view thereof;

FIG. 7 is a right side view thereof;

FIG. 8 is a left side view thereof; and,

FIG. 9 is a perspective view showing the Head rest cover attached to a head rest of a seat.

The short dash lines depict stitching which forms part of the claimed design. The long dash lines illustrate portions of the head rest cover in an environment of use that form no part of the claimed design.
